UNITED STATES PATENT OFFICE.

KARL VÖLLER AND EMIL MÜLLER, OF DUSSELDORF, GERMANY.

SUPPORT FOR GUN-CARRIAGE WHEELS.

1,104,721.

Specification of Letters Patent. Patented July 21, 1914.

Application filed August 15, 1913. Serial No. 794,914.

To all whom it may concern:

Be it known that we, KARL VÖLLER, a subject of the German Emperor, residing at 12 Scharnhorststrasse, Dusseldorf, Germany, and EMIL MÜLLER, a subject of the German Emperor, residing at 27 Jordanstrasse, Dusseldorf, Germany, have invented certain new and useful Improvements in Supports for Gun-Carriage Wheels; and we do hereby declare the following to be a full, clear, and exact description of the invention, such as will enable others skilled in the art to which it appertains to make and use the same.

The invention relates to a support for gun carriage wheels, consisting of two or more parts, which are rigidly connected with the pivot which serves as an axis about which the gun can rotate.

In the accompanying drawing, Figure 1 is a side elevation and Fig. 2 a plan view of the gun carriage and wheel supports. Fig. 3 is a vertical section and Fig. 4 a plan view on a larger scale of the pivot and its attachments. Figs. 5 and 6 are sections of the 25 wheel support through the lines 5—5 and 6—6 respectively of Fig. 2.

The device consists of two or more wheel supports *a*, which are connected so as to be easily dismounted to a pivot *c* provided 30 with four arms *b*, *b'*. The gun with its wheels is set on the wheel supports and connected to the pivot by means of two rods *e* secured by bolts *d* to the sides of the carriage.

35 On the wheel supports guides or racers *f*, and under the supports spiked attachments *g*, are riveted. The rods *e* secured by bolts to the carriage are attached by two eyes *h* (Figs. 2 and 4) to a pivot ring *i*, which is 40 mounted on the upper end of a bearing *k*, formed integral with the arms *b*. The lower end of the bearing has a flange *l* which fits in a circular recess formed in a central enlargement of the arms *b'*, which permits 45 the arms to be closed like a pair of scissors, so that it can be easily packed on an artillery wagon (limber or the like). The wheel supports can also be packed on an artillery wagon and for that purpose can be easily 50 detached from the arms of the pivot. The rods *e* with the eyes *h* can also be easily detached from the pivot ring *i* and during transport of the gun are raised and secured to special bearings *m* of the carriage. The 55 gun is accurately centered by the pivot and

the guides on the wheel supports. The whole arrangement enables the gun to be trained easily and quickly through a large angle, without the elevation of the carriage and gun being affected to any important extent.

In order that the gun should be able to follow the moving target very easily when firing at objects in the air, the wheels and spade should not enter the ground. Guns 60 for defense against balloons, for which carriage support and pivot of the kind described is intended, are provided for this purpose with a hinged spade. When the gun is aimed at targets on the ground, the 65 hinged spade is placed in its operative position and the carriage and wheels rest on the ground. If objects in the air are aimed at, the gun is placed on the wheel supports which are connected with the pivot; this 70 provides a gun carriage with a central pivot for large training angles.

In order that the gun may be easily trained and the elevation of the carriage trail but little changed, the hinged spade is 75 raised, so that the trail only rests on a cover plate which is bent upward. This arrangement, allows the gun to be easily displaced laterally since it has not to be raised by an amount sufficient to withdraw the spade 80 from the ground. In order that the gun when fired should not be displaced rearward, since there is no spade the wheel supports are provided with the spiked attachments *g*.

If the gun is to have a horizontal traverse of 360° on its support, two additional wheel supports are provided, as shown by the chain dotted lines in Fig. 2, and are secured to the arms of the pivot by bolts which 85 are easily released. The edges of the wheel support are beveled (as shown in Fig. 6) and are directed partly at right angles to their length and partly toward the axis of the pivot (Fig. 2). The beveled edges at 90 right angles to their length insure that the gun shall run on to the wheel supports in the axial direction. The edges in the direction of the axis of the pivot enable the gun and wheels to be run on to the wheel support obliquely by moving the trail to one side or the other. The latter manner of running on to the wheel supports would be necessary 95 in the firing position of the gun, if the wheel supports extending to a horizontal 100

traverse of 45° on each side are to be used for larger training angles. In that case the gun when the trail is shifted would run past the wheel supports, but remain connected to the rods *e* and the pivot ring *i*, the wheel supports would then be turned through about 60° around the pivot and the gun would again run on to the supports. In this way it is possible with a wheel support which allows a traverse of 45° to each side to be able to train the gun through considerably larger angles.

An annular wheel support divided across a diameter, will also answer the same purpose, but can not be so easily transported and it is better, if a wheel support is required for 360° , to form it in four parts. In practice it is however sufficient, if two wheel supports are connected by the pivot allowing the gun to be trained through 45° in each direction.

The advantage of these wheel supports is, that they are connected with the pivot by arms and do not form an undivided platform, so that the whole device can be easily and quickly packed and is considerably lighter than a single platform. A further advantage is that the wheels can be centered by the racers and the pivot. Since the wheel supports are provided with spiked attachments, which are pressed into the earth by the whole weight of the gun, it is possible to fire without the spade and to train the gun through the largest angles easily and quickly when aiming at objects in the air.

We claim as our invention:

1. In combination with a gun carriage, a traverse platform having a plurality of wheel supports, a series of arms connecting said supports, pivoting means for said arms at the center of the platform, and arms connected to said pivoting means and also to said gun carriage.

2. In combination with a gun carriage, a traverse platform having a plurality of wheel supports, spikes depending from said supports, a series of arms connecting said supports, pivoting means for said arms at the center of the platform, and arms connected to said pivoting means and also to said gun carriage.

3. A traverse platform for gun carriages comprising a plurality of wheel supports, crossed arms detachably connecting said supports, a pivotal connection between said arms at the center of the platform, and rods carried by said gun carriage and designed to engage the pivot of said arms for centering said gun carriage on said platform, said pivotal connection permitting a relative rotary movement between the carriage and its supports.

In testimony whereof, we have signed this specification in the presence of two subscribing witnesses.

KARL VÖLLER.
EMIL MÜLLER.
